UNITED STATES PATENT OFFICE

LUTHER L. KENNEDY, OF BROOKLYN, NEW YORK, ASSIGNOR TO MERTENTHALER LINOTYPE COMPANY, A CORPORATION OF NEW YORK

TYPOGRAPHICAL COMPOSING MACHINE

Application filed November 6, 1930. Serial No. 493,737.

This invention relates to typographical composing machines, such as linotype machines of the general organization represented in U. S. Letters Patent to O. Mergenthaler, No. 436,532, wherein circulating matrices are released from a magazine by the manipulation of a keyboard and then composed in line, the composed line transferred to the face of a slotted mold, the mold filled with molten metal to form a slug or linotype against the matrices which produce the type characters thereon, and the matrices thereafter elevated and returned through distributing mechanism to the magazine from which they started.

In these machines, the keyboard mechanism usually includes a single series of vertical slides or so-called "key bars" connected to the rear ends of the finger keys and adapted, as the keys are depressed, to trip power-operated devices for the release of the individual matrices through a corresponding series of vertical escapement actuating reeds. When the machines are not in use, it is customary to lock the finger keys to prevent their accidental actuation, and in the earlier commercial machines the means employed for this purpose consisted merely of an adjustable rod arranged horizontally at the back of the keyboard in position to be engaged or disengaged with and from the series of "key bars", as desired.

However, in the later improved machines, changes made in the keyboard mechanism necessitated the provision of a different form of locking means, and the device finally adopted and now in general use is in the form of a rectangular plate slidably mounted on the front plate of the keyboard frame and having elongated slots through which the forward ends of the finger keys extend (see Kennedy Patent No. 1,397,971). This locking plate is effective in locking all the finger keys which control the release of the matrices, but it is ineffective as to the spacer releasing keys, so that to overcome the difficulties arising from such condition, a separate device associated with said locking plate and controlled thereby has recently been proposed for locking and releasing the

spacer key (see the pending application of O. J. Straughan, Serial No. 450,906). While these later keyboard locking devices have been found to be thoroughly practical, they involve an excessive number of parts, are 55 expensive to manufacture and install, and are otherwise objectionable.

The present invention is therefore directed to an improved keyboard locking device which will possess all of the advantages of the later devices, but which will be free from the objections and disadvantages attending the manufacture and use of said devices. In the preferred embodiment illustrated, the improved locking device comprises a sheet metal plate mounted for vertical movement at the back of the keyboard and formed with transverse slots through which the rear ends of all the finger keys (the spacer releasing keys as well as the matrix releasing keys) extend. Means operable at will from the front of the keyboard are also provided for adjusting the plate into or out of locking engagement with said finger keys.

In the accompanying drawings, the invention is shown merely in preferred form and by way of example and as applied to the standard linotype keyboard mechanism, but obviously many changes and variations may be made therein and in its mode of application, which will still be comprised within its spirit. It should therefore be understood that the invention is not limited to any specific form or embodiment, except in so far as such limitations are specified in the claims.

Referring to the drawings:

Fig. 1 is a front elevation of a portion of a linotype machine equipped with the present improvements;

Fig. 2 is a side elevation, partly in section, of the keyboard mechanism, having the improved locking device applied thereto;

Fig. 3 is a rear elevation of the keyboard, showing the locking plate raised to its inactive position; and

Fig. 4 is a view similar to Fig. 3, but showing the locking plate lowered to its active or locking position.

The matrices X and spacers Y (Fig. 1) are stored in their respective magazines X¹, Y¹, 100

and are released therefrom for composition in line by the manipulation of the finger keys of the keyboard. The keyboard includes a series of ninety finger keys A and one or more finger keys B, the former being connected to the escapements (not shown) of the matrix magazine X, and the latter to the escapement actuating lever Y² (Fig. 1) of the spacer magazine Y. The matrix releasing keys A are in the form of straight levers mounted for vertical movement on fixed horizontal pivot rods A¹ secured to the side plates C¹, C², of the keyboard frame C, and which are arranged one above the other so as to sustain the keys in rows at different levels. The spacer key B, on the other hand, is in the form of a rocking lever, comprising the horizontal rod B¹ journaled in the fixed side plates C¹, C², and provided with two arms B² and B³, the arm B² extending forwardly from said rod along one side of the keyboard, and the arm B³ extending rearwardly therefrom at the other side of the keyboard.

The forward ends of the matrix releasing keys A project through elongated slots c formed in the inclined front plate C³ of the keyboard frame C, and the rear ends thereof, as well as the rearwardly extending arm B³ of the spacer releasing key B, project through similar slots c¹ formed in the vertical back plate C⁴ of said frame. Normally, the rear ends of the finger keys A and B are engaged with the lower walls of the slots c¹ but move upwardly in these slots when the forward ends of the keys are depressed, the length of the slots in both the front and back plates C³, C⁴, being sufficient, of course, to permit the vertical movement required.

At their extreme rear ends, the finger keys A are formed with reduced portions a which engage in corresponding notches a¹ formed in a series of vertically movable weighted bars or slides A². When the finger keys are depressed, the slides A² connected thereto are raised, and when the finger keys are released the slides drop by gravity and return the keys to their normal position. The spacer key B is also connected in similar fashion to one of the slides A², but due to the over-balancing weight of the actuating arm B², it is further provided with a spring b to insure its return movement, said spring (Figs. 2, 3 and 4) being connected to the rear arm B³ and anchored to the side plate C² of the keyboard frame.

The slides A², in rising, are adapted to set into motion the power actuated devices which cause the release of the matrices and spacers from their respective magazines. These devices (see Fig. 2) are of ordinary construction and include the two series of trip dogs A³ connected to the upper ends of the slides A², the two series of pivoted yokes A⁴ supported by said dogs and provided with the rotatable cams A⁵, the constantly driven rubber-cov-

ered rolls A⁶ arranged below the cams, and the single series of escapement actuating reeds A⁷ which are lifted by the yokes under the influence of the cams A⁵ when the latter drop into peripheral contact with the rolls A⁶, all as is well understood in the art. 70

So far as described the parts, their construction, and mode of operation are or may be the same as those embodied in the commercial linotype machines and in themselves constitute no part of the present invention, which, as before stated, is devoted to an improved locking device intended to prevent the actuation of all the finger keys when the machine is not in use. 75

As best shown in Figs. 2, 3 and 4, the improved locking device is in the form of a rectangular plate D mounted for vertical movement by screw and slot connections d against the rear face of the fixed back plate C⁴ of the keyboard frame. The plate D (see Figs. 3 and 4) is formed with a series of elongated slots d¹ through which the rear ends of the matrix keys A extend and also with a single slot or notch d² through which the rear arm B³ of the spacer key B extends. When the plate D occupies its raised or inactive position, the slots d¹, d² are adapted to register with the corresponding slots c¹ in the fixed back plate C⁴, so as to permit free vertical movement of the finger keys A and B; whereas, when said plate occupies its lower or active position, the upper walls of the slots d¹, d² will be located out of registry with the slots c¹ and brought into direct engagement with the rear ends of the finger keys A and B so as to prevent their vertical movement. It will be seen, therefore, that by adjusting the plate D downwardly or upwardly, all of the matrix releasing keys A as well as the spacer releasing key B may be locked against actuation or unlocked, as desired. In addition to its locking function, the plate D when adjusted to its active position serves also, in the event of binding or sticking of the finger keys or slides A², to positively restore them to the positions they should normally occupy. 100

The means herein employed for adjusting the locking plate D and which are also intended to hold the same in its inactive position comprise a pair of toggle joints D¹, the upper members D² thereof being pivotally connected to the plate near its opposite ends, and the lower members D³ being similarly connected to the fixed keyboard frame C. 115 The relation of the parts is such that, by collapsing the toggle joints, the locking plate will be lowered so as to shift the upper walls of the slots d¹, d² into engagement with the finger keys A and B, and, conversely, by extending the toggle joints, the locking plate will be raised so as to shift said walls out of engagement with the finger keys. In the present instance, the operation of the toggle joints D¹ is effected manually by means of a 120

fore-and-aft rock shaft D⁴ and a pair of intermediate connecting links D⁵.

The shaft D⁴ (Figs. 1 and 2) is located centrally of the keyboard and journaled in depending cross ribs C⁵ of the keyboard frame C. At its rear end, the shaft D⁴ is provided with a small crank disk D⁶ arranged immediately below the locking plate D and formed with a flat banking surface d³. At its forward end, the rock shaft is provided with a knurled knob or handle D⁷, whereby it may be turned in one direction or the other, as desired. Between its ends, the rock shaft D⁴ is also provided with a collar D⁸, which engages one of the cross ribs C⁵ and which in conjunction with the crank disk D⁶ is adapted to restrain the shaft against endwise displacement.

The links D⁵ are attached at their outer ends to the knuckles of the toggles D¹ and are pivoted at their inner ends eccentrically to the crank disk D⁶, such that by turning the rock shaft D⁴ in its bearings the links will be moved simultaneously by the crank disk in opposite directions and thus extend or collapse the toggles according to the direction in which the shaft is turned.

To limit the rocking movements of the shaft D⁴, a stop pin D⁹ mounted at the back 30 of the frame C adjacent the said shaft is provided and arranged to engage the before-mentioned banking surface d³ of the crank disk D⁶. The stop pin D⁹ (as will be noted from Fig. 3) is positioned so that it will not 35 arrest the rotation of the shaft D⁴, when the latter is turned to extend the toggle joints D¹, until the members D², D³ of the respective toggle joints have been moved to a position past dead center. The plate D (which 40 itself is sufficiently heavy to collapse the toggles against the resistance presented by the shaft D⁴) will therefore be sustained and locked in its raised position without any other means of support.

45 As shown in Fig. 4, the stop pin D⁹, through its engagement with the banking surface d³, also arrests the rotation of the shaft D⁴ when it is turned to collapse the toggles D¹ and thus locates and sustains the locking plate D in its lower position. This latter condition, however, is not essential to the proper operation of the device, since at such times the upper walls of the slots d¹, d² engage the rear ends of the finger keys, which 50 are firmly supported and guided in the slots c¹ of the fixed back plate C⁴ and hence are fully capable of supporting the plate D.

As a result of the foregoing arrangement, a partial turn of the handle D⁷ in a clockwise direction (according to Fig. 1) locks the finger keys A and B of the keyboard against actuation, and a similar turn thereof in the opposite direction releases said keys. By the first operation, the crank disk D⁶, through the links D⁵, collapses the toggles D¹

and lowers the locking plate D to its active position, the upper walls of the slots d¹ in said plate, as well as the upper wall of the notch d², being carried into engagement with the rear ends of the matrix releasing keys A and the rear arm B³ of the spacer releasing key B respectively (see Fig. 4). All of the finger keys are thus locked against accidental depression and brought positively into their normal position. By the second operation, the crank disk pushes the links D⁵ outwardly to extend the toggles D¹ and raise the locking plate D to its inactive position, at which time the upper walls of the slots d¹, d² are carried upwardly out of engagement with the rear ends of the finger keys A and B, the crank disk D⁶ engaging the stop pin D⁹ when the toggles have been completely extended and moved past dead center to hold the locking plate in its raised or inactive position.

Having thus described my invention, what I claim is:

1. A keyboard for typographical composing machines including, in combination, a supporting frame, a series of matrix releasing keys and a spacer releasing key movably mounted therein, and unitary locking means adjustable to active and inactive position and arranged to engage all of said finger keys directly so as to prevent or permit their actuation according to the adjusted position of said locking means.

2. A keyboard for typographical composing machines including, in combination, a supporting frame, a series of matrix releasing keys and a spacer releasing key movably mounted therein, and unitary locking means adjustable to active and inactive position and arranged to engage the rear ends of all of said finger keys directly so as to prevent or permit their actuation according to the adjusted position of said locking means.

3. A keyboard for typographical composing machines including, in combination, a supporting frame, a series of matrix releasing keys and a spacer releasing key movably mounted therein, and a locking plate mounted on the supporting frame and adjustable to active or inactive position as desired, the said plate being formed with portions adapted to be engaged directly with and disengaged from all of the said finger keys as the plate is adjusted to its active and inactive positions, respectively.

4. A keyboard for typographical composing machines including, in combination, a supporting frame, a series of matrix releasing keys and a spacer releasing key movably mounted therein, and a locking plate mounted at the back of the supporting frame and formed with elongated slots through which the rear ends of all of the said finger keys extend, said locking plate being adjustable so as to shift the end walls of its slots into or

out of engagement with the finger keys, as desired.

5. A keyboard for typographical composing machines including, in combination, a supporting frame, a series of finger keys movably mounted therein, a back plate fixed to the supporting frame and formed with elongated slots wherein the rear ends of the finger keys are movably arranged, and a locking plate slidably mounted on the back plate and formed with corresponding elongated slots through which the finger keys extend, the said locking plate being adjustable to active or inactive position so as to shift its slots out of or into registry with those of the fixed back plate and thereby prevent or permit the actuation of the finger keys according to the adjusted position of the locking plate.

20. 6. A keyboard for typographical composing machines including, in combination, a supporting frame, a series of matrix releasing keys and a spacer releasing key movably mounted therein, a locking plate adjustably mounted at the back of said frame and formed with elongated slots through which the rear ends of all said finger keys extend, and manually operated means for adjusting the locking plate so as to shift its slots into or out 25 of engagement with the finger keys, as desired.

30. 7. A keyboard for typographical composing machines including, in combination, a supporting frame, a series of finger keys movably mounted therein and disposed at different levels, a vertically adjustable locking plate mounted at the back of the supporting frame, a pair of toggle joints for adjusting said plate, and manually operated means for 35 extending and collapsing the toggle joints.

40. 8. A keyboard for typographical composing machines including, in combination, a supporting frame, a series of finger keys movably mounted therein and disposed at different levels, a vertically adjustable locking plate mounted at the back of the supporting frame, a pair of toggle joints for adjusting said plate, and manually operated means for 45 extending and collapsing the toggle joints, said locking plate being formed with portions adapted as the toggle joints are collapsed to engage the rear ends of the finger keys directly and as the joints are extended to be 50 disengaged from said keys, for the purpose described.

55. 9. A keyboard as specified in claim 7, characterized by the fact that the manually operated means therein referred to consist of a fore-and-aft rock shaft journaled in the supporting frame and connected at its rear end by a pair of links to the said toggle joints.

60. 10. A keyboard as specified in claim 7, including a stop for arresting the toggle joints when extended past dead center, for the purpose described.

11. A keyboard for typographical composing machines including, in combination, a supporting frame, a series of finger keys movably mounted therein and disposed at different levels, an adjustable locking plate mounted at the back of the supporting frame and formed with portions arranged to engage the rear ends of all of said finger keys, and manually operated means for adjusting the locking plate to its active and inactive positions, said means comprising a pair of toggle joints located at the opposite ends of the locking plate, a fore-and-aft rock shaft journaled in the supporting frame, and a pair of intermediate links attached eccentrically to the rear 70 end of said shaft and connected respectively to the knuckles of said toggle joints.

In testimony whereof, this specification has been duly signed by:

LUTHER L. KENNEDY.
